R. H. BROOKS.

Shovel-Plow.

No. 27,099

Patented Feb. 14, 1860.

UNITED STATES PATENT OFFICE.

ROBERT H. BROOKS, OF GREENVILLE, GEORGIA.

IMPROVEMENT IN PLOWS.

Specification forming part of Letters Patent No. 27,099, dated February 14, 1860.

To all whom it may concern:

Be it known that I, ROBERT HIRAM BROOKS, of Greenville, in the county of Meriwether and State of Georgia, have invented a new and useful Improvement on Plows; and I do hereby declare that the following is a full and exact description thereof, reference being had to the accompanying drawings, and to letters of reference thereon marked.

Figure 1 represents a side view of the plow, made of iron, excepting the handles E E and braces J K, which are of wood.

B is the standard and plow-foot in one piece. A is the beam; C, a curved standard, the upper end of which is turned in the form of a band, through which is inserted the brace J, thus giving support to the handles E E. The lower end of C extends to the continuation of A, where it is connected to handles E E and pieces P P by means of screw-bolt G.

D D are curved iron braces attached to each side of beam A and extending to standard C. They are secured by bolts s s s. The holes H H in braces D D are to regulate, by means of screw-bolt T and holes I I I, the position of standard B. It can thus be elevated or depressed for the various depths of plowing.

The standard B is curved and made flat, as shown at U, in order to fit the mold-board. In the end of foot B the notch X and hole V, as shown in Fig. 2, are placed for purposes

hereinafter described. W is a heel screw, with an arm, a, and point b, as shown in Fig. 5. It is adapted to the following use, viz: The point b is fitted into notch X, the screw W passed through the mold-board O at opening g, also through foot B at hole V, and securely fastened by nut e, thus holding mold-board firmly to its place. Thus by means of the screw W, hole V, and notch X a great variety of mold-boards, arranged with opening g, can be used, adapting this plow to almost every kind of ordinary plowing.

P P are flat pieces of iron, attached by bolts or rivets to each side of beam A at Q, and, extending back, are connected by screw-bolt G with standard C and handles E E. By this arrangement the opening R in the end of beam A is formed. The standard B passes through the opening R, and by the action of screw-bolt F it is held firmly to its place.

What I claim as my invention, and desire to secure by Letters Patent, is—

The arrangement of braces D D C, holes H O V I, screw-bolt T, pieces P P, opening R, beam A, standard B, heel-screw W, notch X, and opening g, constructed as herein described, for the purposes set forth.

ROBERT H. BROOKS.
